UNITED STATES PATENT OFFICE.

HARRY C. BUHOUP, OF CHICAGO, ILLINOIS.

DRAW-GEAR FOR RAILROAD-CARS.

SPECIFICATION forming part of Letters Patent No. 423,727, dated March 18, 1890.

Application filed July 1, 1889. Serial No. 316,201. (No model.)

To all whom it may concern:

Be it known that I, HARRY C. BUHOUP, of Chicago, in the county of Cook and State of Illinois, have invented certain Improvements 5 in Draft Devices for Railroad-Cars, of which the following is a specification.

The object of this invention is mainly to provide a railway-car with a draft device which will take up or neutralize the strains 10 and shocks with a smooth and easy action. To this end I attach my draft-head to the car in such manner that it has a vertical as well as a longitudinal motion in relation to the car. I utilize both motions to compress the 15 springs which resist the pulling and pushing strains. I also combine the parts in such manner as to develop a great amount of friction, which is utilized to assist the springs in resisting the movement of the draft-head.

20 I have represented in the accompanying drawings those constructions which I have found best adapted for general use; but it will be understood by the skilled mechanic after reading this specification that the 25 details of this construction may be greatly modified without changing, essentially, the mode of action or departing from the limits of my invention.

In the accompanying drawings, Figure 1 is a 30 longitudinal vertical section through my draft devices applied to a car, the section being taken on the line $x-x$ of Fig. 2. Fig. 2 is a transverse section on the line $y-y$ of Fig. 1. Fig. 3 is a section on the line $z-z$ of Fig. 1. Fig. 4 is a longitudinal section showing the 35 draft devices in modified form applied to a car. Fig. 5 is a vertical cross-section on the line $y'-y'$ of Fig. 4. Fig. 6 is a cross-section on the line $z'-z'$ of Fig. 4.

40 Referring to Figs. 1, 2, and 3, A represents the car-frame; B, a longitudinally and vertically movable box or casting suspended from the body by swinging links C C'; D, a draw-head mounted in and movable with the box, and E E' vertical springs seated upon the car-frame and the box and acting by their downward pressure to resist any movement of the box and draw-head in relation to the frame.

45 It will be observed that the links C C' are 50 inclined in reverse directions and provided in their lower ends with longitudinal slots c

to receive the transverse pivot-bolts c', by which they are connected to the box. This arrangement causes the box and draw-head to rise when urged endwise in either direction from its normal position, the rising motion being, however, resisted by the springs, so that violent shocks are prevented and the motion taken up with an easy action.

55 The springs are seated in the box, so as to move therewith, and are covered by cap-plates b, fitted to play vertically in the box, but movable endwise therewith and arranged to bear against the overlying friction-plates e, bolted to the under side of the car frame or sills. 60 As these cap-plates b are compelled to slide endwise on the friction-plate whenever the box and the draw-head move, and as they are held by the springs in forcible contact with the plates, a great amount of friction is developed and applied to aid the springs in resisting and checking the end motion of the box and draw-head. Owing to this combined frictional and elastic resistance offered to the 65 movement of the draw-head, my draft devices act gradually and with less violence than those in general use.

70 As an additional means of reducing the shocks, the draw-head may be arranged to slide endwise within the box, a spring f being interposed, as shown, or a spring applied in any of the other methods in which they are commonly used between a draw-head and the support in which it slides. While I have 75 represented in the drawings metallic helical springs, it is manifest that they may be replaced by any equivalent springs known to the skilled mechanic—such, for instance, as an elliptic metal spring, a rubber spring, or a so-called “pneumatic” spring, in which air is 80 confined and compressed to serve as an elastic medium.

85 When the draw-head is capable of end motion within the box, as shown, I provide it with a longitudinal slot f' and pass a connecting-bolt f² transversely through the slot. This bolt, while allowing the motion of the parts in relation to each other, serves as a 90 connection through which the draw-head may act if the ordinary connection at the rear is broken.

95 Passing now to the construction represented

in Figs. 4, 5, and 6, the parts therein shown are substantially the same in construction and arrangement as those in the first form of the apparatus, with the single exception that 5 the links to sustain the box and draw-head are replaced by depending rigid plates g , containing V-shaped slots g' , into which transverse bolts g^2 on the box B are extended. When the box is in its normal or intermediate position, or, in other words, at its lowest point, the rods g^2 rest in the lower middle portions of the slots. When, however, the box is urged endwise, the rods ride upward in one end or the other of the slots, thereby lifting 15 the box and compressing the springs. The springs indirectly, as in the first case, resist the longitudinal movement of the draw-head and their cap-plates act with frictional effect on the overlying plates of the frame.

20 The same letters indicate corresponding parts in all the figures of the drawings.

While the swinging links of Fig. 1 and the slotted plates of Fig. 4 answer all practical purposes, it is to be understood that I may employ in their stead any equivalent connections 25 between the box and body which will cause the box to move vertically as it moves endwise. It is also to be understood that the friction-plates may be varied in form and arrangement, provided only they move endwise with 30 the box and draw-head and are acted upon by the springs, so that the greater the compression of the spring the greater the frictional resistance offered to the fore-and-aft motion of the draw-head.

35 It will be observed that the box B herein described is but a support for the draw-head, which latter may be secured thereto in any appropriate manner, or, if desired in special 40 cases, formed integral therewith. In short, it is to be understood that the draw-head and its connections to the car may be of any form which will admit of the draw-head rising and falling in relation to the car as it moves endwise.

45 While I prefer to employ the springs for the double purpose of resisting the motion of the draw-head and of operating the friction-plates, it is to be understood that I claim the 50 employment of the friction-plates and springs acting thereon, and also the vertically-movable draw-head, separately considered, with springs acting to resist the vertical motion, and this whether the same or separate springs are employed for the two purposes.

55 One of the advantages of my vertically-movable draw-head lies in the fact that a cer-

tain length of movement is necessary in order that springs of sufficient strength may be gradually and practically compressed, so as 60 to offer sufficient resistance to start or stop the cars. In ordinary draft devices the entire movement applied to compress the springs occurs lengthwise of the car. The consequence is that the cars are widely separated 65 in starting the train and permitted to approach each other corresponding distances as the train is brought to a rest. The result is very severe and trying shocks, which result not only in breaking and impairing the draft 70 devices, but also in racking and weakening the car frame and body, owing to the tendency of the superstructure and the load to shift endwise. Under my organization the longitudinal motion of the cars in relation to 75 each other is greatly reduced without reducing or impairing the motion of the springs. The shock and rebound are greatly lessened.

Having thus described my invention, what I claim is—

80 1. In combination with a car, a draw-head movable endwise of the car, springs to resist said end motion, and friction-slides acted upon by the springs to aid in resisting the end motion.

85 2. In combination with a car and a draw-head movable lengthwise thereof, friction-plates to resist said motion and springs acting on said plates to maintain their contact.

90 3. The car, the draw-head support, the connections causing the head to move vertically as it moves endwise, the intermediate springs, and a friction device to resist end motion of the head acted upon by the springs.

95 4. The car, the box or draw-head support, the divergent slotted links connecting the support with the car, the springs seated in the support, the cap-plates movable endwise with the support, and the fixed friction-plates 100 against which the cap-plates slide.

105 5. In combination with the car, the draw-head support, connections causing said support to move vertically as it moves endwise, the vertical springs to resist the rising motion, the draw-head, and a spring to resist the end motion of the draw-head within its support.

In testimony whereof I hereunto set my hand, this 22d day of May, 1889, in the presence of two attesting witnesses.

HARRY C. BUHOUP.
